UNITED STATES PATENT OFFICE.

WILLIAM HENRY RINES, OF RUMFORD FALLS, MAINE.

ELECTROLYTIC APPARATUS FOR ELECTROLYSIS OF METALLIC SALTS.

No. 878,425.

Specification of Letters Patent.

Patented Feb. 4, 1908.

Application filed June 17, 1907. Serial No. 379,427.

To all whom it may concern:

Be it known that I, WILLIAM HENRY RINES, a subject of the King of Great Britain, residing at Rumford Falls, in the county 5 of Oxford and State of Maine, have invented certain new and useful Improvements in an Electrolytic Apparatus for Electrolysis of Metallic Salts; and I do declare the following to be a full, clear, and exact description of 10 the invention, such as will enable others skilled in the art to which it appertains to make and use the same.

My invention has relation to new and useful improvements in electrolytic apparatus 15 for electrolysis of metallic salts, and more especially for solutions of the alkaline chlorides.

In describing my invention I will refer to it for the purpose of this specification as applied for electrolyzing solutions of sodium chlorid, or common salt, with the products of chlorin gas and caustic soda. In all electrolyzing apparatus of whatever type designed for the electrolysis of metallic salts, 25 one of the chief objects sought to be accomplished is to prevent the intermingling of the anodes and cathode products, the efficiency of the process depending to a great extent on the thoroughness with which the same is ac- 30 complished; and one of the main objects of my invention is to provide an improved cell wherein the cathode product is moved by gravity from the sphere of electrolytic action and to so construct the apparatus that the 35 caustic soda falls away freely from the cathode plate as rapidly as formed, thus preventing a diffusion of the same into the anode chamber.

With these objects in view, the invention 40 consists of certain novel features of construction, combination and arrangement of parts as will be more fully described and particularly pointed out in the appended claims.

45 In the accompanying drawings, Figure 1 is a plan view of an apparatus constructed in accordance with the invention; Fig. 2 is a cross sectional view on the line 2--2 of Fig. 1; Fig. 3 is a longitudinal sectional view; and Fig. 4 is an enlarged detail cross sectional view of the cathode plate.

As shown in the drawings, and in accordance with the invention, 1 indicates a suitable tank or receptacle of preferably rectangular 50 form. A plate 2 having deep corrugations, preferably V-shaped in cross section, is ar-

ranged horizontally in and near the bottom and extends entirely across and from one end to a point adjacent the opposite end of said tank or receptacle, leaving a space, 3, between one end of the plate and the adjacent end of the tank. This plate constitutes the cathode of the apparatus and is secured in position to the sides ar 50 one end of the tank or other receptacle by angle irons or plates 4 to insure a good electrical contact therewith. The top of said plate is coated with a non-conducting cement or paint, so as to insulate that particular part of the same, and is perforated between its insulated parts, the pur- 65 pose of which will be shown.

A diaphragm, 5, substantially conforming with the corrugations of said cathode plate, and preferably in the form of a sheet of asbestos paper, is arranged above said plate 75 and divides the tank into anode and cathode chambers, 6 and 7, respectively. A vertical plate 8 is bolted or otherwise fastened to the free end of said cathode plate and extends entirely across the tank or receptacle. The 80 sides and the end of said tank or other receptacle, adjacent the fixed end of said cathode plate, and said plate 5, are provided with linings 9, preferably of acid-resisting, non-conducting cement, which bear on the side 85 and end edges of said diaphragm and thereby securely hold it in position.

A horizontally disposed cover 10 rests on and is supported by the ledges formed by the upper edges of the linings 9 and entirely 90 covers the anode chamber. Said cover is provided with a transverse series of longitudinally alined vertical openings or apertures, 11, through which work or pass upright supporting or lead-in rods, 12, preferably of graphite, to the lower ends of each two of which is an anode, 13, in the form of an oblong graphite block of preferably V- 95 form in cross section. These anodes are arranged in longitudinal series and work in the 100 the corrugations of the cathode plate.

A conductor wire, 14, leads to the apparatus and is provided with a transverse series of parallel branch conducting wires, 15, which contact with the upper or free ends of the upright supporting or lead-in rods, 12, of said anodes. A conductor wire, 16, also communicates with the cathode plate at a suitable point.

In practice the anode chamber is filled 110 with a solution of sodium chlorid, and the cathode chamber filled with water up to with-

in about an inch of the cathode plate. A liquid inert to the products of electrolysis is poured over the water and serves to prevent the carbon dioxids in the air from acting on or carbonating the caustic soda solution in the bottom of the cathode chamber, and also has a balancing medium to retard the diffusion. A current of electricity is then caused to flow through the apparatus and separate the sodium chlorid into its constituent elements, or, in other words, into sodium and chlorin gas. The chlorin gas being an electro-negative element, appears at the positive pole in the anode chamber, from which it is withdrawn through an opening 17 formed in said cover 10. The element sodium appears at the cathode, where it acted on by the water diffusing through the diaphragm and forms caustic soda, with the liberation of hydrogen.

Owing to the construction of the cathode plate, the sodium hydrate is permitted to sink or fall to the bottom of the tank or receptacle, where it is allowed to concentrate until it reaches the desired density, when it may be withdrawn by means of an overflow pipe, 18. The corrugations of the cathode plate serve as ducts for conducting the hydrogen liberated by the action of the sodium to the end of the tank adjacent the free end of the cathode plate, where it escapes through the space 3 between the free end of said plate and the adjacent end of said tank or other receptacle.

35 A funnel 19 extends through said cover 10 and communicates with the anode chamber 6 and a supply pipe 20 has one end arranged above said funnel and has its opposite end free for communication with a source of brine supply. An overflow pipe 21 extends through one side of the tank at a suitable point above the cathode plate and communicates with the anode chamber. This pipe serves to conduct the dilute brine from the anode chamber.

It is thought that from the foregoing description, taken in connection with the accompanying drawings, the construction and operation of the invention will be readily understood without requiring a more extended explanation.

Having described my invention, I claim:

1. In an apparatus of the character described, the combination of a receptacle and a cathode plate having deep V-shaped corrugations in cross section arranged in said receptacle.
2. In an apparatus of the character described, the combination of a receptacle, a cathode plate having deep V-shaped corrugations in cross section arranged horizontally therein, and a diaphragm of asbestos, sub-

stantially conforming with said plate, arranged over the same.

3. In an apparatus of the character described, the combination of a receptacle, a cathode plate having deep V-shaped corrugations in cross section, insulated portions and perforated between said insulated portions maintained horizontally therein, and a diaphragm of asbestos conforming substantially with the shape of said plate arranged above the same.

4. In an apparatus of the character described, the combination of a receptacle, a cathode plate having deep V-shaped corrugations in cross section, insulated portions and perforated between said portions maintained horizontally therein, a diaphragm of asbestos conforming substantially with said plate and arranged over the same, and means for securing said diaphragm in position.

5. In an apparatus of the character described, the combination of a receptacle, a corrugated cathode plate having insulated portions and perforated between said portions extending entirely across and from one end to a point adjacent the opposite end of said receptacle, a vertical plate secured to the free end of said cathode plate and extending entirely across said receptacle, and a diaphragm conforming substantially with the shape of said cathode plate arranged over the same, with means for securing said diaphragm in position.

6. In an apparatus of the character described, the combination of a receptacle, a corrugated cathode plate maintained horizontally therein, and a plurality of anodes arranged in transverse and longitudinal alignment maintained in said receptacle above said cathode plate and working in the corrugations thereof.

7. In an apparatus of the character described, the combination of a receptacle, a cathode plate having deep V-shaped corrugations in cross section, insulated portions and perforated between said portions maintained horizontally therein, a diaphragm conforming substantially with the shape of said cathode plate maintained horizontally above the same, and a plurality of anodes of V-shaped form in cross section maintained in said receptacle above said cathode plate and arranged longitudinally in the corrugations thereof.

In testimony whereof I have hereunto set my hand in presence of two subscribing witnesses.

WILLIAM HENRY RINES.
